ELECTRIC WEFT DETECTOR FOR SHUTTLE
CHANGING LOOMSHerbert A. Whitin, Worcester, Mass., assignor to
Crompton & Knowles Loom Works, Worcester,
Mass., a corporation of Massachusetts

Application December 30, 1948, Serial No. 68,151

7 Claims. (Cl. 139—230)

1

This invention relates to electromechanical weft detecting systems for shuttle changing looms and it is the general object of the invention to provide means by which a false indication of weft exhaustion by the detector incident to a shuttle changing operation will be prevented from initiating another shuttle changing operation.

In a type of multicolor shuttle changing loom which has gone into general use a magazine employing two stacks of reserve shuttles is located adjacent to two shifting shuttle boxes which are normally at rest with respect to the lay, but rise to permit the upper box to receive a selected shuttle from the magazine when the lay is on back center. The depleted shuttle enters the lower box which is temporarily aligned with the shuttle race. The boxes then fall to place the fresh shuttle in picking position and also eject the depleted shuttle. Shifting of the shuttle boxes occurs when the lay is in the forward part of its motion and is ordinarily in progress when the lay is on front center. The weft detector is located at the magazine end of the loom and in order to prevent its breakage by the shifting boxes provision is generally made to move the feeler or weft detector forwardly out of the path of the boxes on shuttle changing beats of the loom.

When an electric weft detector of the side slip type is employed in such a loom it is likely because of its momentum to swing and give a false indication incident to forward and return movement from its normal position to clear the shifting shuttle boxes. When such a feeler is used with an electric weft detecting system there is likelihood that the circuit will be closed by the false indication and a second unnecessary shuttle changing operation will follow.

It is an important object of the present invention to provide the electric weft detector system with a second switch which will be open when the detector is forward of its normal position on shuttle changing beats of the loom, thereby insuring that the detector circuit cannot be closed even though the feeler finger should have a false side slipping movement.

In shuttle changing looms of the type already mentioned it is customary to mount the feeler on an arm or the like pivoted to a fixed stand and it is a further object of the invention to control the second switch in the electric circuit by relative movement of the arm with respect to the stand.

With these and other objects in view which will appear as the description proceeds, the inven-

2

tion resides in the combination and arrangement of parts hereinafter described and set forth.

In the accompanying drawings, wherein a convenient embodiment of the invention is set forth,

Fig. 1 is a side elevation of part of a multicolor weft replenishing loom showing the lay, shuttle boxes and cover therefor in cross section,

Fig. 2 is an enlarged plan view partly in section looking in the direction of arrow 2, Fig. 1, showing the weft detector in normal position in full lines and in indicating position in dotted lines,

Fig. 3 is an enlarged vertical section on line 3—3 of Fig. 2,

Fig. 4 is an enlarged diagrammatic view of the structure shown at the left of Fig. 1 indicating the parts in two different positions,

Fig. 5 is an enlarged transverse section on line 5—5, Fig. 4, showing the second switch in closed position,

Fig. 6 is a view similar to Fig. 5 but showing the switch open, and

Fig. 7 is a diagram showing the electric circuit used with the invention.

Referring more particularly to Fig. 1, the loom frame 10 supports a reserve shuttle magazine M having front and back stacks 11 and 12, respectively, of reserve shuttles which may have weft of two different characteristics. The shuttles of the front stack are supported by a lever 13 connected by rod 14 to another lever 15. The latter is connected by a rod 16 to control mechanism not shown herein but well understood.

The shuttles of the rear stack 12 rest on a support 17 and the lowest shuttle in stack 12 is in front of a plunger 18 controlled by a lever 19 which in turn is connected to another rod 20 which also extends to the control mechanism to which rod 16 extends. When a shuttle from the front stack is to be released rod 16 is depressed to effect rocking of lever 13, whereupon the bottom shuttle of stack 11 falls into a common compartment 21 below stack 11 and in front of the bottom shuttle in stack 12. If, on the other hand, a replenishing operation involves a shuttle

from the rear stack rod 20 will be depressed so that the plunger 18 will move the lowest shuttle of stack 12 into the common compartment 21. A support 22 extending rearwardly from the lay 23 will hold the released shuttle until the lay reaches back center.

Shuttle change is effected by means of a gang G of shuttle boxes having upper and lower cells or boxes 25 and 26, respectively, mounted on a box lifter rod 27. These shuttle boxes are normally down as shown in Fig. 1 so that the top

shuttle box 25 is active and receives a shuttle on every other beat of the loom. When a shuttle changing operation is called rod 27 is lifted to place the lower cell or shuttle box 26 in active position to receive the oncoming depleted shuttle and at the same time the upper shuttle box 25 is raised to a position where it can receive a reserve shuttle in the compartment 21.

The shuttle box structure has pivoted thereto a cover 28 provided with a stud 29 for cooperation with a cam 30 fixed to the magazine in stationary position. The boxes ordinarily shift while the lay is in the forward part of its motion when the stud 29 is forward of the cam 30 and as the shuttle boxes rise the stud is caused to register with the cam so that the subsequent rearward movement of the lay will rock the cover in a counterclockwise direction as viewed in Fig. 1 to open the top of shuttle box 25 so that it can receive the reserve shuttle from compartment 21.

The weft detector D is located on the same side of the loom as the magazine and is in front of the shuttle boxes. Ordinarily this detector is in stationary position and enters the shuttle box 25 to detect the condition of weft in the shuttle therein when the lay beats up to front center. Since the boxes shift at front center breakage of the detector would result unless it were moved forwardly. Provision is usually made for mounting the detector so that it can be moved forwardly by the structure shown at the left of Fig. 1.

A stationary support 35 fixed with respect to the magazine M carries a stud or similar pivot 36 on which is mounted a detector supporting arm 37. A spring 38 interposed operatively between the arm 37 and a part of the support 35 normally holds the arm 37 in the position shown in Fig. 1 with the detector in its normal detecting position. A pressure member 40 is pivoted as at 41 to the arm 37 and is normally in such position that the cover 28 moves under it when the lay approaches front center. When the boxes are rising, however, incident to a shuttle changing operation the cover engages the member 40 and forces the latter forwardly against a pin 42 on the arm 37, thereby rocking the latter in a clockwise direction as viewed in Fig. 1 around the pivot 36. The detector D is thus moved forwardly to a position where it cannot interfere with or be broken by the shifting boxes 25 and 26.

The matter thus far described is of common construction and may be made as set forth in prior Patent No. 2,103,800.

The control mechanism for the rods 16, 20 and 27 includes a solenoid designated at S in Fig. 7. When this solenoid is energized due to indication of weft exhaustion by detector D a shuttle changing operation is initiated. This solenoid may be the same as that shown in the aforesaid patent and control the various parts of the magazine and shuttle boxes as set forth therein.

In the past it has been customary to make the weft detector of two prongs of opposite polarity which will be insulated from each other during detecting operations when there is sufficient weft in the shuttle being detected, but when the weft is depleted a ferrule carried by the shuttle will be exposed and electrically connect the prongs of the detector, thereby energizing the solenoid.

A detector of this type requires a ferrule on every bobbin used in the loom and in order to avoid the expense of these ferrules it is proposed to use a side slip electro-mechanical detector which will operate with the usual bobbin made without a ferrule. Such a detector is shown for

instance in Figs. 2 and 3 wherein the arm 37 is shown as being provided with a foot 45 to which a detector carrier plate 46 is bolted as at 47. Plate 46 has secured thereto an upstanding stud 48 on which is pivotally mounted a detector arm 49. A coil spring 50 surrounds stud 48 and has one end thereof connected to the arm or finger 49 and has the other end thereof connected to a drum or shell 51 surrounding the stud 48. A set screw 52 affords means for fastening the drum in adjusted angular position to the stud 48 for the purpose of varying the force exerted by the spring 50.

Supported by the arm 49 at one side of the pivot stud 48 is a horizontal tube 55 in which is slidably mounted a detector finger 56 the rear end of which has a tip 57 for engagement with the bobbin B in shuttle box 25. A light compression spring 58 within the tube 55 surrounds the forward end of the rod or finger 56 and serves in well-known manner to hold the latter and therefore the tip rearwardly in detecting position. When sufficient weft is present during the detecting operation to resist side slipping movement of the tip 57, the rod 56 moves forwardly against the action of spring 58 without causing substantial angular motion of the arm 49. When the bobbin is depleted of weft, however, a smooth surface thereof is presented to the tip and the latter slides laterally to the dotted line position shown in Fig. 2, thereby causing angular motion of the arm 49.

As shown in Fig. 3 the plate 46 has secured to the under side thereof a switch 60 which has a control plunger or pin 61 which when pushed inwardly, or rearwardly toward arm 49 as viewed in Fig. 2, causes the switch to be open, but when the plunger moves forwardly the switch automatically closes. Position of the plunger is controlled by a preferably resilient plate or arm 63 pivoted as at 62 with respect to the plate 46. This arm extends to the left as viewed in Fig. 2 to a position behind a finger 64 which projects forwardly from arm 49 and then downwardly, see Fig. 3. The plunger 61 normally exerts a forward pressure on the leaf spring 63 which, however, is not sufficiently strong to overpower the spring 50. When the detector finger 56 slides forwardly on a non-indicating beat of the loom the finger 64 maintains the left end of the leaf spring 63 in rear position, thereby keeping the plunger 61 in its normal rearward position with respect to the switch 60 to keep the latter open. When the detector indicates weft exhaustion, however, angular movement of arm 49 moves the finger 64 forwardly away from controlling position with respect to the leaf spring 63 and the latter permits the plunger 61 to move forwardly and close switch 60. In this manner the detector effects closure of the switch 60 whenever it has a side slipping movement, as when indicating weft exhaustion.

It will be apparent that the greater part of the weight of the arm 49 and parts supported thereby is at one side of the pivot 48, and as the support arm 37 moves the detector to positions forward of its normal position the detector is likely to swing in a counter-clockwise direction as viewed in Fig. 2 about the stud 48 to give a false indication of weft exhaustion, thereby effecting closure of the switch 60, although at this time it is undesirable to have the switch closed. Under these conditions the detector would call a second shuttle changing operation of the loom unless provision were made to prevent closure of the detector circuit.

In order that the false closing of the switch 60 may be prevented from energizing the solenoid S when the detector is moved forwardly there is provided a second switch 70 having a spring contact 71 for engagement with a fixed contact 72. The switch 70 is provided with a plunger 73 similar to plunger 61, except that its effect is the reverse of the latter named plunger. When the plunger is moved into the switch 70 the contacts 71 and 72 are in electric engagement with each other as shown in Fig. 5, but when the plunger 73 is free to move forwardly under action of the resilient contact 71 the two contacts are open, see Fig. 6.

Switch 70 is mounted on the detector support arm 37 by means of a plate 75 fastened as at 76 to the arm 37. The plunger 73 is positioned for engagement with the support 35, and when the parts are held in their normal position as shown in Fig. 1 the support 35 effects movement of the plunger 73 to the position shown in Fig. 5. At this time the switch 70 is in the full line position shown in Fig. 4. When the detector is moved forwardly, however, by engagement of the cover 28 with member 40 the carrier 37 swings upwardly around pivot 36 to the dotted line position shown in Fig. 4. This effects lifting of the switch 70 relatively to support 35 with consequent movement of the plunger 73 downwardly with respect to the switch 70. The resilient contact 71 thereupon moves the plunger 73 to the position shown in Fig. 6 and moves away from contact 72, thereby opening the switch 70.

The circuit for operating the aforesaid solenoid, shown in Fig. 7, is normally as follows: transformer T, a wire 80, solenoid S, wire 81, normally open detector switch 60, wire 82, normally closed control switch 70, and wire 83 back to the transformer. When switch 60 is closed by a normal and proper indication of weft exhaustion by the detector solenoid S will be energized, because at this time switch 70 is closed. During a shuttle changing operation, however, when the detector D gives a false indication, control switch 70 will be open and the circuit shown in Fig. 7 cannot be closed, therefore the solenoid will not be energized.

From the foregoing it will be seen that the invention sets forth simple means by which a side slipping electromechanical weft detector can be used on a shuttle changing loom without danger that the detector circuit will be closed by a false indication of the detector when the latter is moved out of the path of the shifting shuttle boxes incident to a shuttle changing operation of the loom. This result is accomplished by having a second or control switch in the circuit normally closed but so controlled as to open and therefore interrupt the detector circuit whenever the detector is moved forwardly by the box cover 28. Rearward movement of the lay from its front center position while the boxes 25 and 26 are rising permits spring 38 to return the detector to its normal position, but by the time this normal position is attained the detector arm 49 will have returned to its normal position so that detector switch 60 will be open when switch 70 closes.

Having thus described the invention it will be seen that changes and modifications of the foregoing specific disclosure may be made without departing from the spirit and scope of the invention.

What is claimed as new is:

1. In a shuttle changing loom having a lay provided with shuttle boxes which shift incident to a shuttle changing operation of the loom, a weft detector normally positioned to detect the condition of weft in one of said boxes, means giving the detector a movement in a direction away from the boxes on shuttle changing operations of the loom, the detector tending due to said movement to give a false indication of weft exhaustion, shuttle changing controlling electric circuit means including a normally open electric switch closed whenever the detector indicates weft exhaustion and including also a normally closed switch, said circuit means being closed only when both switches are closed, and means effecting opening of the normally closed switch on shuttle changing operations of the loom.
2. In a shuttle changing loom having a lay provided with shuttle boxes which shift incident to a shuttle changing operation of the loom, a weft detector normally positioned to detect the condition of weft in one of said boxes but receiving a movement derived from the lay and due to shifting of the shuttle boxes in a direction away from the boxes on shuttle changing operations of the loom and tending due to said movement to give a false indication of weft exhaustion, shuttle changing controlling electric circuit means including a normally open electric switch closed whenever the detector indicates weft exhaustion and including also a normally closed switch, said circuit means being closed only when both switches are closed, and means effecting opening of the normally closed switch by a force derived from the lay on shuttle changing operations of the loom.
3. In a shuttle changing loom having a lay provided with shuttle boxes which shift incident to a shuttle changing operation of the loom, a weft detector normally positioned to detect the condition of weft in one of said boxes but receiving a movement derived from the lay and due to shifting of the shuttle boxes in a direction away from the boxes on shuttle changing operations of the loom and tending due to said movement to give a false indication of weft exhaustion, shuttle changing controlling electric circuit means including a normally open electric switch closed whenever the detector indicates weft exhaustion and including also a normally closed switch, said circuit means being closed only when both switches are closed, and means dependent upon shifting movement of the shuttle boxes effecting opening of the normally closed switch by a force derived from the lay on shuttle changing operations of the loom.
4. In a shuttle changing loom having a lay provided with shuttle boxes which shift incident to a shuttle changing operation of the loom, a weft detector normally positioned to detect the condition of weft in one of said boxes but receiving a movement by a force derived from the lay in a direction away from the boxes on shuttle changing operations of the loom and tending due to said movement to give a false indication of weft exhaustion, shuttle changing controlling electric circuit means including a normally open electric switch closed whenever the detector indicates weft exhaustion and including also a normally closed switch, said circuit means being closed only when both switches are closed, and means effecting opening of the normally closed switch by a force derived from
5. In a shuttle changing loom having a lay provided with shuttle boxes which shift incident to a shuttle changing operation of the loom, a weft detector normally positioned to detect the condition of weft in one of said boxes, means giving the detector a movement in a direction away from the boxes on shuttle changing operations of the loom, the detector tending due to said movement to give a false indication of weft exhaustion, shuttle changing controlling electric circuit means including a normally open electric switch closed whenever the detector indicates weft exhaustion and including also a normally closed switch, said circuit means being closed only when both switches are closed, and means effecting opening of the normally closed switch on shuttle changing operations of the loom.
6. In a shuttle changing loom having a lay provided with shuttle boxes which shift incident to a shuttle changing operation of the loom, a weft detector normally positioned to detect the condition of weft in one of said boxes but receiving a movement derived from the lay and due to shifting of the shuttle boxes in a direction away from the boxes on shuttle changing operations of the loom and tending due to said movement to give a false indication of weft exhaustion, shuttle changing controlling electric circuit means including a normally open electric switch closed whenever the detector indicates weft exhaustion and including also a normally closed switch, said circuit means being closed only when both switches are closed, and means effecting opening of the normally closed switch by a force derived from the lay on shuttle changing operations of the loom.
7. In a shuttle changing loom having a lay provided with shuttle boxes which shift incident to a shuttle changing operation of the loom, a weft detector normally positioned to detect the condition of weft in one of said boxes but receiving a movement derived from the lay and due to shifting of the shuttle boxes in a direction away from the boxes on shuttle changing operations of the loom and tending due to said movement to give a false indication of weft exhaustion, shuttle changing controlling electric circuit means including a normally open electric switch closed whenever the detector indicates weft exhaustion and including also a normally closed switch, said circuit means being closed only when both switches are closed, and means effecting opening of the normally closed switch by a force derived from the lay on shuttle changing operations of the loom.
8. In a shuttle changing loom having a lay provided with shuttle boxes which shift incident to a shuttle changing operation of the loom, a weft detector normally positioned to detect the condition of weft in one of said boxes but receiving a movement by a force derived from the lay in a direction away from the boxes on shuttle changing operations of the loom and tending due to said movement to give a false indication of weft exhaustion, shuttle changing controlling electric circuit means including a normally open electric switch closed whenever the detector indicates weft exhaustion and including also a normally closed switch, said circuit means being closed only when both switches are closed, and means effecting opening of the normally closed switch by a force derived from

the lay on shuttle changing operations of the loom.

5. In a shuttle changing loom having a lay provided with shuttle boxes which shift incident to a shuttle changing operation of the loom, a weft detector normally positioned to detect the condition of weft in one of said boxes, means giving the detector a movement in a direction away from the boxes on shuttle changing operations of the loom, the detector tending due to said movement to give a false indication of weft exhaustion, shuttle changing controlling electric circuit means including a normally open electric switch closed whenever the detector indicates weft exhaustion and including also a normally closed switch, said circuit means being closed only when both switches are closed, and means dependent upon shifting movement of the shuttle boxes and movement of the lay effecting opening of the normally closed switch on shuttle changing operations of the loom.

6. In a shuttle changing loom having a lay provided with shuttle boxes which shift incident to a shuttle changing operation and having a weft detector normally positioned to detect the condition of weft in one of said shuttle boxes but having a movement derived from the lay in a direction away from the shuttle boxes during a shuttle changing operation which causes the detector to give a false indication of weft exhaustion, a normally open electric switch closed whenever the detector indicates weft exhaustion, a normally closed electric switch, shuttle changing controlling electric circuit means closed to initiate a shuttle changing operation only if both switches are closed, and means effecting open-

ing of the normally closed switch during a shuttle changing operation to prevent a false indication by the weft detector from effecting closure of the electric circuit means.

5. In a shuttle changing loom having a lay provided with shuttle boxes which shift incident to a shuttle changing operation of the loom, a stationary support member, a weft detector supporting member mounted on the stationary member and moved relatively thereto by a force derived from the lay on a shuttle changing operation of the loom, an electric switch mounted on one of said members and normally maintained closed by the other member when said members are in normal position but opened when the detector supporting member is moved by the lay, a weft detector on the detector supporting member tending to give a false indication of weft exhaustion when the supporting member therefor is moved by the lay, a normally open electric switch closed whenever the detector indicates weft exhaustion, and shuttle changing controlling electric circuit means closed only when both of said switches are closed.
